UNITED STATES PATENT OFFICE.

DANIEL F. DALTON, OF WATERBURY, CONNECTICUT, ASSIGNOR TO THE
CHAPMAN & ARMSTRONG MANUFACTURING COMPANY, OF SAME PLACE.

CLASP.

SPECIFICATION forming part of Letters Patent No. 378,238, dated February 21, 1883.

Application filed July 9, 1887. Serial No. 243,812. (No model.)

To all whom it may concern:

Be it known that I, DANIEL F. DALTON, a citizen of the United States, residing at Waterbury, in the county of New Haven and State of Connecticut, have invented certain new and useful Improvements in Clasps; and I do hereby declare the following to be a full, clear, and exact description of the invention, such as will enable others skilled in the art to which it applies to make and use the same.

My invention is adapted to all of the uses to which garment-clasps are ordinarily applied—for example, stocking-supporters, drawers-supporters, &c.—and has for its object to produce a device of this class which may be manufactured at the minimum expense, will hold the garment positively without danger of tearing, will be easy to clasp and unclasp, and will not easily get out of repair.

The novel features of my invention consist in the relative construction of the engaging portion of the clasp and of the guard, and their combination with each other, as hereinafter described, and as clearly pointed out in the claims.

With these ends in view I have devised the simple and novel construction of which the following description, in connection with the accompanying drawings, is a specification, numbers being used to indicate the several parts.

Figure 1 is an elevation showing the guard raised; Fig. 2, a similar view showing the guard pushed down—that is, in the engaging position; Fig. 3, an edge view corresponding with Fig. 2; and Fig. 4 is a plan view of the plate from which the guard is formed.

The device consists of two parts or members only, which I shall designate as A and B.

Part A is made of wire and is formed as follows: 1 denotes an eye or loop, which is formed at the center of the piece to adapt it for attachment in use. This eye or loop may, of course, be made of any desired shape or size to adapt it to receive a strip of textile fabric, or to be stitched or eyeleted to a strip of fabric or to a garment. I have shown simply a loop adapted to receive a strip of textile fabric, as in the ordinary stocking-supporter, that being sufficient to illustrate the principle of my invention. 2 denotes arms connected to the eye or

loop. These arms lie substantially parallel with each other, and are provided at their lower ends with hooks 3, which are adapted to be passed through the material of the garment upon which the clasp is used.

Part B, the guard, is made of sheet metal and consists of a plate, 4, having slots extending inward from opposite sides at the center, so that two pairs of tongues are formed. Both tongues of the upper pair are turned backward, as shown, and curved around arms 2, forming sleeves 5, which slide upon said arms. Both tongues of the lower pair are bent forward, as shown, and curved to form sleeves 6, which, when the guard is pushed down, as in Figs. 2 and 3, pass over points 7 of hooks 3, thus holding the fold of the garment that has been engaged firmly in place, so that it cannot possibly become detached, no matter how often the wearer may change position—as, for example, in getting up and sitting down, or children at play. The arms are preferably made of spring-wire, so that when the guard is raised the hooks will spring away from each other, as shown in Fig. 1. The effect of this is to cause sufficient friction between sleeves 5 and the arms, so that the guard will be firmly held in any position in which it may be placed.

The operation is so simple as to hardly require description. The garment is caught by the thumb and finger and the hooks are passed through one or more thicknesses, which avoids all danger of tearing. The guard is then slipped down and sleeves 6 passed over the points of the hooks, as shown in Figs. 2 and 3, which renders it impossible for the clasp to become detached, no matter what changes in position may be made by the wearer.

I claim—

1. In a garment-clasp, a pair of spring-arms having hooks at their lower ends, in combination with a guard-plate provided with sleeves fitting and adapted to slide upon said arms and provided with a guard portion adapted to cover the said hooks, the upper ends of the arms being formed into a T-shaped loop having a straight upper bar and projecting laterally over said guard-plate.

2. In a garment-clasp, a pair of spring-arms having hooks at their lower ends, in combination with a guard-plate provided with sleeves fitting and adapted to slide upon said arms and provided with a guard portion adapted to cover the said hooks, the upper ends of the arms being formed into a T-shaped loop having a straight upper bar and projecting laterally over said guard-plate.

tion with a guard-plate, 4, slotted laterally to form tongues which are bent, the upper pair toward the rear and the lower pair toward the front of said plate, thereby forming a pair of 5 sleeves surrounding and sliding upon said arms, and a second pair of sleeves upon the front face of the plate, said plate being adapted to pass down behind the points of the hooks

and the second pair of sleeves to inclose the front of the hooks, as set forth.

In testimony whereof I affix my signature in presence of two witnesses.

DANIEL F. DALTON.
